(57) **CLAIM**

The ornamental design for a television receiver as shown and described.

DESCRIPTION

FIG. 1 is a perspective view of a first embodiment of a television receiver showing our new design;

FIG. 2 is a front elevational view thereof;

FIG. 3 is a left side elevational view thereof;

FIG. 4 is a top plan view thereof; and

FIG. 5 is a bottom plan view thereof.

FIG. 6 is an enlarged top plan view of the television receiver along the line 6-6 of FIG. 4;

FIG. 7 is an enlarged right side elevational view of the television receiver along the lines 7-7 and 7'-7' of FIG. 6; FIG. 8 is an enlarged left side elevational view of the television receiver along the lines 8-8 and 8'-8' of FIG. 6; and

FIG. 9 is an enlarged right side elevational view of the television receiver along the lines 9-9 and 9'-9' of FIG. 6. FIG. 10 is a perspective view of a second embodiment of a television receiver showing our new design; FIG. 11 is a left side elevational view thereof; and

FIG. 12 is a top plan view thereof.

FIG. 13 is an enlarged top plan view of the television receiver along the lines 13-13 of FIG. 12;

FIG. 14 is an enlarged front elevational view of the television receiver along the lines 14-14 and 14'-14' of FIG. 13; and FIG. 15 is an enlarged front elevational view of the television receiver along the lines 15-15 and 15'-15' of FIG. 13.

FIG. 16 is a perspective view of a third embodiment of a television receiver showing our new design; FIG. 17 is a front elevational view thereof;

(Continued)

FIG. 18 is a left side elevational view thereof;
 FIG. 19 is a top plan view thereof; and
 FIG. 20 is a bottom plan view thereof.
 FIG. 21 is an enlarged top plan view of the television receiver along the line 21-21 of FIG. 19
 FIG. 22 is an enlarged right side elevational view of the television receiver along the lines 22-22 and 22'-22' of FIG. 21;
 FIG. 23 is an enlarged left side elevational view of the television receiver along the lines 23-23 and 23'-23' of FIG. 21; and,
 FIG. 24 is an enlarged right side elevational view of the television receiver along the lines 24-24 and 24'-24' of FIG. 21.
 The evenly dashed broken lines illustrate portions of the television receiver that form no part of the claimed design. The dot-dash broken lines defining the boundaries of the claimed design form no part of the claimed design.
